UNITED STATES PATENT OFFICE

MARTIN L. JENSEN, OF CULLOM, ILLINOIS

BUNDLE-CARRIER ATTACHMENT

Application filed August 6, 1927. Serial No. 211,169.

My invention relates to bundle carrier attachments for grain binding machines.

One of the objects of the invention is to provide a simple, practical and effective device or attachment of the class specified.

Another object of the invention is to arrange for the automatic operation of the bundle carrier so as to automatically throw or dump the bundles from the machine.

10 Another object of the invention is to secure effectiveness, simplicity and accuracy of operation.

Other objects of the invention will appear and be pointed out hereinafter.

15 In the accompanying drawings:

Fig. 1 is a longitudinal section of a portion of a harvesting or binding machine provided with a bundle carrier attachment embodying my invention, said section being taken 20 on line 1—1 in Fig. 2;

Fig. 2 is a transverse section taken on line 2—2 in Fig. 1;

Fig. 3 is a cross section taken on line 3—3 in Fig. 1;

25 Fig. 4 is a cross section taken on line 4—4 in Fig. 3; and

Fig. 5 is a view of a detail of construction.

Referring to the drawings, I show a portion of a binding machine involving a bundle 30 hopper 1 having packers 2, 2 and a trip finger or member 4. This mechanism is found in varied use on certain types of binders and so of itself is not a part of my invention.

The bundle carrier for receiving bundles 35 from the hopper or chute 1 is shown generally at 5 and involves a plurality of rods 6, 6 arranged lengthwise of the machine as well shown in Fig. 1 and in position below the end of hopper or chute 1 so as to receive bundles therefrom, as shown in Fig. 2.

In accordance with my invention bundles received by the bundle carrier will be permitted to collect until any desired number, as for example four (4) or five (5), are accumulated and then these bundles will be automatically dumped or thrown from the machine and thus manual or foot power of the operator for this purpose will not be necessary. In the arrangement set forth herein, provision is made for the accumulation of

five (5) bundles, and the automatic dumping of the same, but the mechanism may be modified so that a different number of bundles may be accumulated before automatic discharge and may also be modified in other 55 ways.

In this arrangement the plurality of bundle carrying rods 6, 6 arranged side by side to receive and hold the bundles are mounted upon a rock shaft 7, which is capable of being turned or rocked into a supporting or holding position, as shown in Fig. 1, in which position the bundles will be sustained and held during accumulation, and may also be turned or rocked so as to swing the bundle 60 supporting or left-hand portions (Fig. 1) downwardly so as to permit the bundles to slide off from said rods 6, 6 and be thrown or dumped from the machine upon the ground, or otherwise, as desired. 70

To accomplish this swinging movement of the holding or supporting rods 6, 6 to permit holding and dumping, suitable mechanism is provided automatically operable by the operating mechanism of the machine. 75 This may consist of a rocker arm 8 mounted on rock shaft 7 and a driving link 9 pivotally connected with arm 8 and also pivotally connected by means of a wrist pin at 10 with a casting or bracket 11 bolted on a mutilated gear wheel 12, which is provided for the greater operation of its periphery with gear teeth 13, but which has a portion 14 which is stripped or devoid of gear teeth. This wheel has a stop finger 15, preferably formed as part of the bracket or casting 11, and this stop finger 15 serves to engage and hold a stop roller 16 on a rod 17 which is pivoted at 18 and provided with a retractile spring 19 which tends normally to hold its right- 80 hand end (Fig. 1) in up or elevated position which will cause roller 16 to engage stop finger 15. In this position the wheel 12 will be prevented from turning or rotating and the driving link 9 will be held against movement even though the weight of bundles on the carrying rods 6, 6 may tend to depress said rods 6, 6 and cause arm 8 to push against driving link 9 so as to tend to turn wheel 12.

Teeth 13 on wheel 12 are adapted to mesh 100

with teeth 20 on a pinion 21 on a shaft 22, which is one of the rotating or driving shafts of the binding machine and is normally rotated during the operation of the machine, as shown for example, by the sprocket chain 23 (Fig. 1) driving a shaft 24 which is gear connected by gear wheels 25 and 26 with said shaft 22. The teeth of gear wheel 12 and pinion 21 are normally out of mesh, however, due to the absence of gear teeth on the section 14 of wheel 12 and hence wheel 12 is normally stationary and is held normally locked in such stationary position by rod 17, as previously explained.

Mechanism is provided, however, for permitting or causing wheel 12 to turn sufficiently to release supporting or carrying rods 6, 6 and drop or discharge the bundles, when a predetermined or sufficient number of bundles has been dropped or discharged out of said bundle mechanism. While this mechanism may vary it may consist of mechanism associated with the bundle tripping or discharging mechanism of the machine, as for example, a link 30 pivotally connected at 31 to the swinging arm 32 carrying the bundle discharge finger 4, (Fig. 2) said link 30 being pivotally connected with a rod or arm 33 pivotally mounted on a shaft 34 which also carries a ratchet wheel 35 having teeth 36. Crank arm 33 carries a dog 37 controlled by a spring 38 so that dog 37 normally will engage teeth 36 and turn wheel 35 as said link 30 is reciprocated up and down by the operation of swinging arm 32. In this way each time a bundle passes member 4 and drops into the bundle carrier, the link 30 will cause arm 33 to be depressed and then to rise and thereby cause dog 37 to turn wheel 35 a fraction or portion of a revolution. The number of teeth 36 on wheel 35 is the number of bundles it is desired to have the bundle carrier contain before the bundles are automatically dumped. In this case five (5) such teeth 36 are shown, it being desired to have five (5) bundles in the carrier before dumping. Thus, the passage of each bundle into the bundle carrier will cause wheel 35 to turn one-fifth of a revolution and five (5) bundles will cause such wheel 35 to turn a complete revolution.

The shaft 34 carrying wheel 35 also carries a disc or wheel 40 and this in turn carries a tappet roller 41. The latter is adapted to strike the aforesaid rod 17 each time shaft 34 performs a complete revolution. Hence, when five (5) bundles have passed to the bundle carrier and wheel 35 has been turned a complete revolution, roller 41 will strike and actuate rod 17, depressing the right-hand end of the same, referring to Fig. 1. This will swing the left-hand end of rod 17 upwardly, causing roller 16 thereon to rise above the end of stop finger 15 and thereby release finger 15 and wheel 12. This permits

wheel 12 to be turned in the direction indicated by the arrow in Fig. 3, due to the weight of bundles on carrying rods 6, 6 lowering said rods and permitting rock shaft 7 to turn and cause arm 8 to push link 9 and thereby move or turn wheel 12 in the direction indicated. This downward movement of rods 6, 6 permits the bundles to slide or roll downwardly off from said rods and thus to be dumped or discharged from the machine onto the ground or otherwise, as desired. The downward movement of the rods 6, 6 and discharge of the bundles would, however, leave the supporting or holding rods 6, 6 in a downward position where further operation of the mechanism in the desired manner would not be possible were it not that said rods 6, 6 were automatically restored to their upper or holding position after the bundles thereon were discharged. This may be accomplished by the gear wheel arrangement previously described, that is, the cooperating wheels 12 and 21, the former being stripped of teeth for a portion of its periphery. The operation of these wheels is such that when rod 17 is swung upwardly so as to release stop finger 15, the wheel 12 will turn freely a sufficient amount to allow the bundle rods 6, 6 to dump or discharge the bundles, but at this point wheel 12 has turned sufficiently to bring its teeth 13^a into engagement with teeth 20 on pinion 21. Therefore, pinion 21 will by its rotation, turn wheel 12 the balance of a revolution, until teeth 20 again come out of mesh with teeth 13^a, and at this time the wheel 12 will have actuated driving link 9 sufficiently to swing arm 8 back to normal position, as shown in Fig. 1 and thereby swing rods 6, 6 upwardly to their bundle holding position, as shown in said figure. This operation will be repeated automatically from time to time, the desired number of bundles being accumulated in the bundle carrier and then the latter being automatically operated or tripped so as to dump or discharge those bundles and again permit the accumulation of another set of bundles which are likewise automatically dumped or discharged.

It will be understood that changes and modifications may be made without departing from the spirit of the invention.

What I claim is:

1. The combination with a binding machine of a bundle carrier, and means for automatically dumping the said carrier and means for automatically returning the same to carrying position, said first mentioned means including bundle carrying rods, said bundle carrying rods being arranged to receive the bundles and to be operated by the bundles so received.

2. The combination with a binding machine of a bundle carrier automatically operating the bundle carrier by the mechanism

of the binder, means for automatically discharging a predetermined number of bundles, said means including a ratcheted counting wheel, a tappet-carrying disk, a tappet roller carried thereon, a shaft mounted for rotation arranged to transmit motion from the said wheel to the said disk.

3. The combination with a binding machine of a bundle carrier and means whereby the weight of the bundles in the carrier tends to operate said carrier so as to discharge said bundles, and means for automatically holding the bundle carrier against discharge until a predetermined number of bundles shall have been accumulated in the carrier.

4. The combination with a binding machine of a bundle carrier and means whereby the weight of the bundles in the carrier tends to operate said carrier so as to discharge said bundles, means for automatically holding the bundle carrier against discharge until a predetermined number of bundles shall have been accumulated in the carrier, and tripping mechanism for automatically actuating the bundle carrier mechanism to permit discharge when a predetermined number of bundles has accumulated.

5. The combination with a binding machine of a bundle carrier having swinging bundle holding members mounted to permit them to be swung by the weight of bundles upon them, means normally holding said arms against swinging movement, and means operable by the mechanism of the machine for releasing said arms and permitting them to discharge the bundles.

6. The combination with a binding machine of a bundle carrier having swinging bundle holding rods mounted to permit them to be swung by the weight of bundles upon them, means normally holding said arms against swinging movement, means operable by the mechanism of the machine for releasing said arms and permitting them to discharge the bundles, and means for automatically restoring said arms to holding position, said restoring means including a mutilated gear, the pinion driven by the binding machine operating the said mutilated gear, a rocker arm, a driving link connected to the said gear and said rocker arm, a rock shaft for mounting the rocker arm, said bundle holding rods being attached to the said rock shaft for movement therewith.

7. The combination with a binding machine of a bundle carrier having swinging bundle holding arms mounted to permit them to be operated to discharge bundles by the weight of such bundles, means for holding said arms against discharge of the bundles comprising a rotary member connected with said arms so as to normally maintain the same in holding position, means for holding said rotary member normally against rotation, and mechanism operable by the passage

of bundles from the machine into the bundle carrier for actuating said holding means to release the rotary member when a predetermined number of bundles have passed into the carrier.

8. A bundle carrier attachment comprising means for supporting bundles and mechanism for automatically operating said bundle supporting means so as to dump or discharge the bundles when a predetermined number thereof have come into the carrier, said mechanism for dumping the bundles including a stop rod associated with a stop finger, said stop rod arranged to release the said stop finger, thereby actuating the said bundle supporting means for dumping the bundles.

9. A bundle carrier attachment comprising means for supporting bundles, and mechanism for automatically dumping or discharging the bundles from such supporting means, said mechanism for dumping the bundles including a stop rod associated with a stop finger, said stop rod arranged to release the said stop finger, thereby actuating the said bundle supporting means for dumping the bundles.

10. A bundle carrier attachment comprising movable bundle supporting means mounted to permit the support or discharge of bundles, means for normally holding said supporting means in holding position, and mechanism for causing the movement of said supporting means to discharge bundles when a pre-determined number of bundles have passed into the carrier, said holding means including a driving link, a gear, a wrist pin supported and actuated by the said gear connecting said link to said gear, a stop finger on said gear, a stop rod co-acting with said stop finger and arranged to release the said movable bundle support.

11. A bundle carrier attachment having movable bundle supporting means mounted to permit movement into supporting and discharging positions, mechanism normally holding said supporting means in holding position, said mechanism including a stop device, and means for actuating said stop device to permit movement of the supporting means to discharge position when a predetermined number of bundles have passed on to said supporting means; said stop device including a stop rod and a stop finger associated therewith, a driving link interconnected at one end thereof with the movable bundle supporting means and the other end mounted and arranged to operate the said stop finger.

12. A bundle carrier attachment having movable bundle supporting means mounted to permit movement into supporting and discharging positions, mechanism normally holding said supporting means in holding position, said mechanism including a stop device, means for actuating said stop device,

- to permit movement of the supporting means to discharge position when a predetermined number of bundles have passed on to said supporting means, said stop device including a stop member and a movable member cooperating therewith, and means actuated by the passage of bundles into the carrier for operating said last mentioned member when a predetermined number of bundles have passed; said means for causing movement into holding position including a driving link, actuating means therefor, said driving link operating to cause said movement into holding position.
13. The combination with the swinging bundle holding arms or rods of a rock shaft on which the same are mounted, means for normally holding said rock shaft against operation, and means operated by the passage of bundles from the machine for permitting the rock shaft to turn when a predetermined number of bundles have passed into the carrier, said rock shaft and said bundle holding arms being actuated by the weights of the bundles supported on and by the said arms.
14. The combination with the swinging bundle holding arms or rods of a rock shaft on which the same are mounted, means for normally holding said rock shaft against operation, means operated by the passage of bundles from the machine for permitting the rock shaft to turn when a predetermined number of bundles have passed into the carrier, and means for automatically restoring said swinging arms to holding position, said automatic restoring means including a wrist pin driven by the machine, a driving link connected thereto, the said driving link connected to the said rock shaft for imparting rocking motion thereto.
15. The combination with the swinging bundle holding arms or rods of a rock shaft on which the same are mounted, means for normally holding said rock shaft against operation, means operated by the passage of bundles from the machine for permitting the rock shaft to turn when a predetermined number of bundles have passed into the carrier, said last mentioned means comprising a crank pin bracket connected with the rock shaft and provided with a stop, a pivoted stop rod for normally engaging said stop, and means operated by the bundles for actuating said pivoted rod.
16. The combination with the swinging bundle holding arms, of a rock shaft on which the same are mounted, a crank pin bracket connected with said rock shaft, a stop finger carried by the bracket, a pivoted rod normally engaging said stop finger, spring means tending to hold said rod in normal position, and tripping mechanism comprising a rotary shaft carrying a ratchet wheel and also carrying means for operating said

pivoted rod and mechanism for operating said ratchet wheel.

17. The combination with the swinging bundle holding arms, of a rock shaft on which the same are mounted, a crank pin bracket connected with said rock shaft, a stop finger carried by the bracket, a pivoted rod normally engaging said stop finger, spring means tending to hold said rod in normal position, tripping mechanism comprising a rotary shaft carrying a ratchet wheel and also carrying means for operating said pivoted rod and mechanism for operating said ratchet wheel, a mutilated gear attached to and rotating with said bracket and a driving pinion for operating said mutilated gear; said rotary member being provided with gear teeth, and a gear wheel having teeth adapted to cooperate with the teeth on said rotary member.

18. The combination with the swinging bundle carrying arms of a rock shaft on which the same are mounted, and automatic mechanism for controlling the rocking thereof.

19. The combination with the swinging bundle carrying arms, of means for swingingly supporting the same, and trip mechanism comprising a rotary member provided with a stop, and means for engaging and releasing said stop.

20. The combination with the bundle carrying arms and means for swingingly supporting the same, of a stop mechanism for releasing said arms, means for controlling said stop comprising a ratchet mechanism, and means for restoring said arms after release by said stop comprising a rotary pinion or gear wheel cooperating with a mutilated gear.

In witness whereof, I hereunto subscribe my name this 27th day of July, A. D., 1927.

MARTIN L. JENSEN.
